UNITED STATES PATENT OFFICE.

JOHN P. NIKONOW, OF PITTSBURG, PENNSYLVANIA.

DYNAMO-ELECTRIC MACHINE.

No. 883,043.

Specification of Letters Patent.

Patented March 24, 1908.

Application filed April 13, 1907. Serial No. 368,029.

To all whom it may concern:

Be it known that I, JOHN P. NIKONOW, a subject of the Czar of Russia, residing at Pittsburg, in the county of Allegheny and State of Pennsylvania, have invented certain new and useful Improvements in Dynamo-Electric Machines, of which the following is a specification.

The present invention relates to an improved field construction for dynamo electric machines, such as direct current motors, dynamos, revolving field alternators and synchronous motors.

In the operation of dynamos considerable difficulty is frequently encountered in obtaining a good commutation and maintaining a constant electromotive force owing to the distortion of the field flux by the armature flux induced by the current flowing through the armature leads or inductors.

The object of this invention has been to obviate this difficulty by reducing this armature reaction to a minimum, and this result is accomplished by the provision of a novel field construction in which the various poles comprise a series of cores, each core forming a part of an independent magnetic circuit. With this construction a series of air gaps are introduced into the path of the armature flux and the reluctance of the said paths is increased to such an extent as to effectively split up the armature flux into a plurality of comparatively small and local circuits which do not distort the field flux to any marked extent.

For a full description of the invention and the merits thereof and also to acquire a knowledge of the details of construction and the means for effecting the result, reference is to be had to the following description and accompanying drawings, in which:

Figure 1 is a side elevation of the upper portion of the dynamo electric machine constructed in accordance with the present invention. Fig. 1^a is a similar view of the lower portion of a machine embodying a modification of the invention. Fig. 2 is a transverse vertical sectional view through the upper portion of a machine embodying the invention. Fig. 2^a is a similar view through the lower portion of a machine and shows a modification. Fig. 3 is a side elevation of a portion of a machine. Fig. 4 is a view showing the invention as applied to a revolving field. Fig. 5 is a diagrammatic view showing the magnetic circuits under

one of the poles. Fig. 6 represents by means of curves the intensity of the field and armature fluxes and also of the reluctance flux. Fig. 7 shows a modification for compound wound machines.

Corresponding and like parts are referred to in the following description and indicated in all the views of the drawings by the same reference characters.

The invention is shown as applied to a multi-polar machine and in the preferred embodiment shown in Figs. 1 and 2 the field construction of the machine comprises a main or intermediate yoke 1 which is in the nature of a continuous ring and carries the inwardly extending and radially disposed cores 2. The armature 3 is mounted in the usual manner so as to rotate between the inner extremities of the cores 2. Located upon each side of the cores 2 are supplemental cores 4 and 5, the corresponding supplemental cores of each pole being counteracted by a separate yoke member whereby a series of independent magnetic circuits is produced within each pole. As shown in the drawings the supplemental cores 4 are magnetically connected to arms 6 projecting inwardly from the yoke member 7 which is in the nature of a ring secured to one side of the main yoke 1 by means of the bolts 8 and magnetically insulated therefrom. A similar yoke member 9 is secured to the opposite side of the main yoke 1 and is formed with the inwardly extending arms 6^a which are magnetically connected with the supplemental cores 5. These two yoke members 7 and 9 are held spaced from the main yoke 1 by means of insulating washers 10, whereby an air gap is produced between the various yoke pieces of the field construction. If found desirable the yoke members 7 and 9 may as in the present instance be formed with the spiders 11 having the bearings 12 located at their central portions within which the armature shaft is journaled. The several cores of each field pole are magnetically insulated from each other and this result may be accomplished either by means of the washers 13 or by filling blocks 14 of some non-magnetic material. The exciting field coil 15 of each pole is wound about the several cores collectively so that when the exciting current is passed through the coil independent magnetic circuits are produced in the various cores.

As indicated by the dotted line *x* in Fig. 1

the path followed by the flux produced by the action of the field coils upon the main cores 2 extends from one of the cores 2 across the air gap into the body of the armature, 5 through the body of the armature, across the second air gap into the opposite core 2, and through the main yoke 1 into the first mentioned core 2. In a similar manner the path of the flux produced by the auxiliary cores 4 and indicated by the dotted line *y* can be traced through the armature and the pole pieces 6 and through the yoke member 7. The path of the flux produced by the auxiliary cores 5 and indicated at *z* follows a 10 similar course with the exception that it passes through the yoke member 9. As will be readily apparent from Fig. 5 this construction confines the armature flux to small local circuits immediately under each of the 15 cores, whereas were it not for the air gaps between the several cores of each pole piece the circuits of the armature flux would extend throughout the entire pole and thereby distort the main flux. In this figure the armature leads or inductors 16 are shown as 20 located under one of the pole pieces and the circuits of the armature flux are indicated by the dotted lines 17. The effect of the armature flux upon the main flux is indicated 25 diagrammatically in Fig. 6 wherein the line A—B represents the armature surface in one pole division between two neutral lines, while the ordinates represent the flux density at the respective points. The curve 18 is derived 30 from the armature flux and the curve 19 from the field flux. By combining these two curves I obtain the curve 20 which represents the resultant distribution of the flux. From a study of these curves it will be 35 apparent that while there are slight variations in flux density for each of the cores, yet the variation for the whole pole is considerably less than would be the case were the core one solid piece as in the usual construction.

40 A modification is shown in Figs. 2^a and 1^a in which the yoke of the machine comprises a pair of spaced rings 21, and the field poles are each formed of a pair of magnetically insulated cores 22 carried by or magnetically connected to arms 23 projecting from the respective yokes 21. In the present instance the two yokes 21 are connected by a number of bolts and held spaced from each other by 45 means of washers 24 surrounding the bolts. With this construction a two path field is produced instead of the three path field as in the former instance and two distinct magnetic circuits can be traced through each of the pole pieces. With compound wound machines as indicated in Fig. 7 it may be found 50 desirable to restrict the series winding to one of the cores 22 as indicated at 25 and thereby reinforce the field on that side where it is most distorted by the armature flux, while 55 the main field winding as indicated at 26

extends around the two cores 22 collectively. Under some conditions it may be found desirable to employ jack screws 27 for forcing the outer ends of the pole pieces inwardly and holding them firmly against the arms carried 60 by the yoke members.

This invention also has the advantage of reducing the field leakage and of enabling the pole pieces of a multi-polar machine to be placed closely together, since the lines of force do not flow from the adjacent side of one pole piece to the adjacent side of the next pole piece but from the far side of one pole piece to the adjacent side of the next pole piece.

Under some conditions it may be found desirable as indicated in Fig. 3 to give the central core 2 of the field poles laminated construction. These laminations have the 70 general direction of the armature shaft so as to extend transversely across the path of the armature flux and increase the reluctance of the said path. This is due to the thin films of air between the various laminations which 75 constitute air gaps.

In Fig. 4 the principle of the invention is shown as applied to a revolving field and comprising magnetically insulated members 28 and 29 mounted upon the shaft 32 so as to 80 rotate therewith in the usual manner. These members 28 and 29 carry the corresponding and radial arms 30 and 31 respectively which 85 form the cores around which the exciting coils of the field are wound. The core of each of the field poles comprises a pair of the arms 30 and 31 which are spaced or magnetically insulated from each other so as to provide two 90 distinct paths for the field flux. This construction operates in a manner identical with 95 that previously described to break up the 100 armature flux into a plurality of small circuits, thereby preventing the same from distorting the main flux to such a marked degree as would otherwise be the case.

Having thus described the invention, what 105 is claimed as new is:

1. A dynamo electric machine comprising a plurality of poles each formed of a series of cores constituting parts of distinct magnetic circuits, the cores being arranged to cause 110 the magnetic circuits to flow from the far side of one pole to the adjacent side of the next pole.
2. A field construction for dynamo electric machines comprising a series of magnetically independent yokes, and a plurality of poles each being formed of a series of cores constituting parts of distinct magnetic circuits, the cores of each pole being arranged to cause the 115 magnetic circuits to flow from the far side of one pole to the adjacent side of the next pole.
3. A field construction for dynamo electric machines comprising a plurality of magnetically insulated yokes in the form of rings, and poles carried by the yokes, each pole com- 120

prising a plurality of magnetically insulated cores connected to the respective yokes, the cores of each pole being arranged to cause the magnetic circuits to flow from the far side of one pole to the adjacent side of the next pole.

4. A field construction for dynamo electric machines comprising a main yoke, cores carried by the main yoke, a yoke member located upon each side of the main yoke and magnetically insulated therefrom, and auxiliary cores located upon opposite sides of the before mentioned cores and magnetically connected to the respective yoke members.

5. A field construction for compound wound dynamo electric machines comprising poles formed of a plurality of core pieces each having an independent magnetic circuit, the series winding being limited to a selected one

of the cores while the main winding surrounds the several cores collectively.

6. A field construction for compound wound dynamo electric machines comprising a series of magnetically separated yokes, and pole pieces magnetically connected to the various yokes, each pole comprising a plurality of core pieces each forming part of an independent magnetic circuit, the series winding being confined to a selected one of the cores of each pole, while the main winding surrounds the cores collectively.

In testimony whereof I affix my signature in presence of two witnesses.
